(57) **CLAIM**

I claim the ornamental design for a combined automobile grill and electric generators, as shown and described.

DESCRIPTION

FIG. 1 is a front elevational view of a combined automobile grill and electric generators;

FIG. 2 is a rear elevational view thereof;

FIG. 3 is a top plan view of the right side thereof;

FIG. 4 is a bottom plan view of the left side thereof;

FIG. 5 is a side elevational view thereof; and,

FIG. 6 is a side elevational view thereof.

The broken line drawing is for environmental purposes and does not form part of the claimed design.
